UNITED STATES PATENT OFFICE

GEORGE A. MACREADY, OF LOS ANGELES, CALIFORNIA

RECOVERABLE WELL PACKER AND FLUID SAMPLER

Application filed August 2, 1923, Serial No. 655,206. Renewed May 8, 1925.

This invention relates to deep well apparatus and more particularly to a well packer and fluid sampler.

The invention further relates to a method 5 for so handling a packer and sampler that the entire structure can be utilized in taking well product samples at different levels progressively to facilitate in determining when and where to cement off, and at the same 10 time to insure recovery of the apparatus.

An object also is to provide for the constant motion of parts of the apparatus after the packer body has been and is temporarily seated and while samples are being taken 15 from the strata below the packer. Another object is to provide for circulation during constant motion so as to aid in preventing the parts from sticking in the hole.

An object is to provide a packer and sampler in combination with means adapted to be compressed at the upper end of the seated packer to form a substantially water-tight seal at the top of the packer body to fill crevices and thus prevent downward flow of water 25 past the packer and insure a reliable test of the well product below the packer body.

An object is to provide an apparatus including a lowering structure and a packer body telescopically attached thereto, and to 30 provide means forming a wad to be expanded into the well hole to form a tight packing pad by the downward movement of the lowering structure. An object is to provide a locking means to prevent the relative telescoping of the packer members into the lowering structure in the event that a temporary 35 resistance should be encountered by the packer, for the purpose of preventing the expansion of the packing wad at an undesired 40 and unintentional depth in the hole.

An object is to provide means for effecting a downward circulation of circulating fluid to the bottom element of the packer, and to provide for the removal of such means when 45 desired and the insertion, in its place, of a bailing means; and further, an object is to provide for circulation within the packer after it is seated and while the bailing means is in place in the apparatus.

An important object is to provide an ap-

paratus including a packer body to be arranged in a temporarily stationary position in the well hole and including a lowering structure adapted to be constantly reciprocated and combining a bailing means to be 55 associated stationarily with the seated packer and provide for bailing from below the packer while the lowering structure forming a part of the apparatus is being reciprocated.

Other objects and advantages will be made 60 manifest in the following specification of an embodiment of the invention illustrated in the accompanying drawings, wherein:

Figure 1 is a diagrammatic sectional view showing the apparatus, including the lowering structure and a packer inserted, with the packer body resting on its seat prior to the expansion of the sealing wad.

Fig. 2 is a diagrammatic sectional view showing the recovery of the lock unit and a 70 subsequent expansion of the sealing wad.

Fig. 3 is a diagrammatic sectional view showing the apparatus as installed and operating for bailing below the seated packer body and showing the lowering pipe partly 75 lifted and adapted for reciprocation.

Fig. 4 is a longitudinal section showing the packer unit and the lower portion of the lowering pipe, and showing the packer retainer sleeve bearing against the packer body, 80 with the ports of the discharge sleeve uncovered.

Fig. 5 is a cross section on line 5-5 of the packer stem.

Fig. 6 is a side elevation of a wad cartridge. 85

Fig. 6' is a side elevation of a modified form of wad cartridge.

Fig. 7 is a cross section through the wad cartridge.

Fig. 11 is a longitudinal section of the locking unit expanded.

Fig. 12 is a cross section on line 12-12 of Figure 11.

My present invention involves a novel 100

method and apparatus for taking formation samples at different levels in a deep well to aid in determining the best or proper level at which to cement off above the oil bearing formation.

While various changes and details of an apparatus by which my improved method may be practiced and utilized, for purposes of illustration a form of apparatus is here shown as comprising a substantial, rather elongated, conical packer body 2, which may be of metal, and which is adapted to make a more or less snug fit in a previously cut seat S in the well hole W which is being drilled, and in which it is desired to ascertain the proper level for cementing off.

The packer body is hollow and attached to its lower end by a suitable nipple 3 and coupler 4 is a suitable length of perforated pipe 5. Attached to the upper end of the packer body 2 is a hollow spindle 2^a, the upper end of which is provided with an external, annular shoulder *a*. This combination of members may be regarded as the "packer unit" of the apparatus. Preferably, the spindle 2^a somewhat clears the adjacent surrounding surface at the upper end of the packer body 2, so as to allow for a certain or possible bowing of the spindle during use of the apparatus.

Means for lowering the packer unit to the seat S in the well hole includes, as here shown, an outer or lowering pipe or tube 8 of such diameter as to be capable of passing down into the well.

To the lower end of the pipe 8, which is obviously built up of pipe sections, is attached what I may term a discharge sleeve 9, these parts being threaded together as at 10. This discharge sleeve 9 has a bore of sufficient diameter to permit the entrance of the upper end of the packer spindle 2^a, which end, when telescoping down in the discharge sleeve 9, serves to substantially close radial discharge ports 11 in the sleeve and thus prevent the material escape of the circulating liquid which may be forced down through the lowering pipe 8.

Into the lower end of the discharge sleeve 9 is secured a portion 12 of a hollow sleeve or shoe 13; the upper end of the part 12 thereof being a shoulder *b* and this is adapted to be engaged by the shoulder *a* of the packer spindle 2^a when, in the assemblage of the parts, the apparatus is in position to be lowered into the well hole. In other words, during the lowering in of the apparatus the packer unit is suspended by the engagement of the shoulder *a* with the opposing shoulder *b* provided at the lower end of the lowering unit which may be regarded as comprising the outer pipe 8, the sleeve 9 and its attached shoe 13. As above stated, when the head of the spindle 2^a is telescoped in the

discharge sleeve 9, the head forms a closure for the discharge ports 11.

It is desirable to provide a substantially leak-proof packing at the head of the seated packer body 2 in the well hole to prevent the trickling or seepage downward of well liquid through interstices which may occur between the body 2 of the packer and the stone or formation seat S cut therefor in the well hole. To that end, in the assembly of the apparatus preparatory to lowering in, there is mounted upon the packer spindle 2^a an expansible or disruptive and deformable medium which can be dislodged from the spindle 2^a and compressed solidly and effectively against the wall formation at the head of the packer body. A form of such sealing means or medium may consist of a cartridge including a sleeve-like spool of fibers or cords 15 which, for convenience, may be laid longitudinally on a fragile spool or tube 16. The fibrous sealing means may be wrapped or encased as in the jacket or winding of tape 17. This cartridge is adapted to be slid down upon the spindle 2^a and against the upper end of the packer body 2 and is followed, preferably, by a conical expanding device 18 sliding on the spindle 2^a and the larger end of which is disposed against the lower, abutting or ramming end of the shoe 13, as is clearly shown in Figure 1.

In Fig. 6' the wad cartridge is shown as of a considerable length, this cartridge consisting of two or more of the cartridges shown in Fig. 6 arranged end to end and separated by a spacing ring 18', which engages the ends of the spools or tubes 16.

Since the sealing cartridge is to be disrupted and expanded against the well wall as soon as the packer body 2 is seated, and since this disruption is secured by the relative downward movement of the shoe 13 and the lowering unit after the packer is seated, it is desirable to provide means for preventing the cartridge from being destroyed at any intermediate point, as by the relative upward movement of the packer unit should the latter encounter momentary resistance sufficient to hold it while the lowering unit is descending. Therefore, I provide an automatically acting locking means to secure the packer unit against upward, accidental movement in the lowering unit and therefore to protect the sealing cartridge.

A form of automatic locking means is clearly shown in Figures 9 to 12, inclusive, as including a unit assembly comprising a tubular head 20 having a reduced lower leading end 20^a designed to telescope in the socket *c* provided in the upper end of the packer spindle 2^a and which socket is provided with a conical ground seat *d*, Figure 4. The head 20 has an upwardly extending, reduced neck 20^b which has a shoulder 20^c which slidably fits in a hollow mandrel 21 having a lower

tapered end or nose 22 abutting against the upper end of the head 20. The neck 20^b is hollow, as the head 20, and this provides for the downward flow of water from an inside pipe 23 which is attached to the upper end of the mandrel 21.

Slidably mounted on the nose portion 22 of the mandrel is a set of expansible, externally toothed slips 25 which are shown as provided with channels 26 on their inner faces running on complementary guideways 27 along the tapered nose 22 of the mandrel.

When the assembled parts of the apparatus are in position to be initially lowered into the well hole, the head 20 rests on the upper end of the spindle 2^a and the slips 25 are in their normal, expanded position, Figure 11, and rest on the upper end of the head 20. The slips 25 are maintained in their expanded position by the expander 21 which rests with its nose 22 against the slips 25. Upon any tendency upon the part of the packer spindle 2^a to move upwardly in the lowering pipe, the slips 25 immediately become effective by a downward pressure against the contiguous portion of the lowering pipe 8 to bite into the same and thus lock the packer unit against upward movement so that the interposed cartridge device 15 is therefore protected against destruction prematurely. The slips 25 serve no other purpose than to assist in placing the cartridge device 15 in position for operation.

After the packing unit has been seated on the seat S, as in Figure 2, the locking device including the slips 25 is withdrawn as a unit as by means of any fishing spear F, Figure 2, which is adapted to enter the upper end of the pipe 23, one function of which is to form a weight of sufficient effectiveness to hold the slips in expanded position. When the fishing spear F has grappled in the pipe 23, the latter, with all of the locking members forming the locking or clamping unit, can be withdrawn from the apparatus. The initial upward movement of the mandrel 21 retracts its nose 22 to a sufficient degree to allow the slips 25 to contract or free themselves from the engaged pipe 8. Further upward movement brings the mandrel nose against the shoulder 20^c of the neck 20^b and therefore upward movement of the pipe 23 lifts the locking unit from the outer or lowering pipe 8.

Upon the removal of the locking means, the outer pipe 8, which obviously is suspended during operations by any suitable elevator E, may then be lowered so that its shoe 13 will force the disrupting cone 18 on the spindle 2^a, with the result that the cartridge of fiber 15, or whatever other material or character the cartridge may have, is crushed and forced outwardly and compressed to form a good seal or packing ring R, Figure 3, around the head of the packer body 2. Preferably the disrupting cone 18 is of a material soft

enough to be mashed out and away so that the shoe 13 can ultimately be lowered down against the upper end of the packer body 2, as seen in Figure 4, with the result that the packer and the packing ring are sent firmly 70 home.

An object is to provide not only an apparatus and method for facilitating the determination of the cementing level, but also to provide a method for insuring the recovery 75 of the apparatus after the test has been completed, and further, to provide for the taking of a sample of the well product.

Therefore, during the lowering of the packer to its seat, liquid is forced down through the outer pipe 8 and, since the discharge ports 11 of the sleeve 9 are closed by the spindle 2^a when it is in the lowering position, the circulation liquid will be driven down through the hollow lock unit and the hollow packer unit and discharged from the extreme lower end of the same into the hole, and thence pass upwardly around the outside of the apparatus.

After the packer body has been seated and the packing ring R compressed in place, the parts are then in such position that liquid forced down through the outside pipe 8 will pass around the spindle 2^a and out through the discharge ports 11 and thence flow upwardly around the outside of the pipe 8, therefore keeping the well hole open and preventing the pipe from freezing.

It is desirable, after the packer body has been seated, also to reciprocate the outer pipe 8 in the well hole above the packer, and for this purpose there is attached to the upper end of the outer pipe a head fitting 30, having a lateral connection 31 to which may be attached a circulation hose 32. Above the fitting 30 is a part 33 in which is arranged a packing 34 compressed by a follower 35 on a "polish" section 36 of piping which forms a part of a string 37 extending down into the casing and through which the well hole below the packer may be bailed to obtain a sample.

To the part 33 at the head of the outer pipe there may be attached the elevator E by which the outer pipe is lowered away and also by which it is reciprocated after the packer is seated at such intervals as may be desired to keep it from sticking.

The bailing pipe 37 has at its lower end a nipple 38 designed to enter the socket c at the upper end of the packer spindle 2^a and engage the ground seat d so as to make a sufficiently tight joint thereon to cut off inflow of water or circulating liquid which may be forced through the fitting 30 down in the outer pipe 8.

From the above it will be seen that the bailing pipe 37 rests in a stationary manner on the packer stem, since the latter is held stationary on its seat, and while the packer

bailing pipe 37 is stationary, the string of outer pipe 8 can be alternately raised and lowered by the elevators E to keep it free in the hole. The packing 34 in the head of the apparatus makes a tight joint on the upper polished section 36 on the bailing pipe.

After the bailing pipe has been installed, samples may be taken through the bailing pipe to disclose the nature of the well product encountered below the seated packer.

10 After the test has been completed, the entire apparatus may be recovered from the hole and used in other holes, or may be again run down in a given hole after the same has been 15 deepened as may be determined necessary according to the results of the test.

It may be desirable to provide for a rotation of the packer body while it is being lowered into the hole, and this may be accomplished in any suitable manner and by any means, as for instance the spindle 2^a may have a noncircular cross section so as to engage in the shoe 13 without rotation, so that if the lowering pipe is rotated, the packer body 25 also would be rotated.

Further embodiments, modifications and variations may be resorted to within the principle of the invention.

What is claimed is:

30 1. A drilled well packer and sampler including a tubular externally tapered packer body adapted to be lowered to a previously drilled seat in a well hole, tubular means for lowering the packer body to its seat and slidably connected to the packer, a device for locking the packer body and tubular lowering means to prevent their relative motion, said device locking by expansible slips and removable from the well when the packer is seated, means at the lower end of the tubular lowering means to drive the packer down tightly into the seat by dropping the tubular lowering means on the packer, thereby deforming the packer or seat or both to form a 45 liquid tight seal.

2. A drilled well packer and sampler including a packer body adapted to be lowered to and against a previously drilled seat in the well hole, tubular means for lowering the 50 packer body to its seat, means at the head of the packer body to be expanded at the head of the seated packer body to form a substantially leak-proof seal, a tubular spindle attached to the packer body and slidably connected with the tubular lowering means, said packing means consisting of a cartridge formed of a packing material mounted on said spindle and adapted to be crushed to form a water-tight seal at the head of the seated packer body, and a locking device arranged in 55 the said tubular lowering means for preventing relative telescopic action of the spindle in the tubular means to prevent premature effective expansion of the packing cartridge.

55 said locking device including expansible slip members held in a normally expanded position in the tubular means while the apparatus is being lowered in, said slip members being held in effective expanded position by a retractive means adapted to be removed from the tubular means when the packer body is ultimately seated, whereby to permit the said cartridge to be expanded by downward movement of the tubular means.

60 5. A drilled well packer and sampler consisting of the following units: a first unit comprising a tapered packer body, a packing and hollow spindle adapted to be lowered to and driven into a previously formed seat in the well hole and equipped with shoulders to limit 65

pansible slip members held in a normally expanded position in the tubular means while the apparatus is being lowered in.

3. A drilled well packer and sampler including a packer body adapted to be lowered to and against a previously drilled seat in the well hole, tubular means for lowering the packer body to its seat, means at the head of the packer body to be expanded at the head of the seated packer body to form a substantially leak-proof seal, a tubular spindle attached to the packer body and slidably connected with the tubular lowering means, said packing means consisting of a cartridge formed of a packing material mounted on said spindle and adapted to be crushed to form a water-tight seal at the head of the seated packer body, and a locking device arranged in the said tubular lowering means for preventing relative telescopic action of the spindle in the tubular means to prevent premature effective expansion of the packing cartridge, said locking device including expansible slip members held in a normally expanded position in the tubular means while the apparatus is being lowered in, said slip members being held in effective expanded position by a retractive means adapted to be removed from the tubular means when the packer body is ultimately seated.

4. A drilled well packer and sampler including a packer body adapted to be lowered to and against a previously drilled seat in the well hole, tubular means for lowering the packer body to its seat, means at the head of the packer body to be expanded at the head of the seated packer body to form a substantially leak-proof seal, a tubular spindle attached to the packer body and slidably connected with the tubular lowering means, said packing means consisting of a cartridge formed of a packing material mounted on said spindle and adapted to be crushed to form a water-tight seal at the head of the seated packer body, and a locking device arranged in the said tubular lowering means for preventing relative telescopic action of the spindle in the tubular means to prevent premature effective expansion of the packing cartridge, said locking device including expansible slip members held in a normally expanded position in the tubular means while the apparatus is being lowered in, said slip members being held in effective expanded position by a retractive means adapted to be removed from the tubular means when the packer body is ultimately seated, whereby to permit the said cartridge to be expanded by downward movement of the tubular means.

5. A drilled well packer and sampler consisting of the following units: a first unit comprising a tapered packer body, a packing and hollow spindle adapted to be lowered to and driven into a previously formed seat in the well hole and equipped with shoulders to limit

the total sliding movement and facilitate the withdrawal from the well after a test and slidably connected to the lowering means so that in certain positions it closes ports in the lowering means, thereby directing the circulation flow to discharge below the bottom of the packer; a second unit comprising a tubular lowering means slidably connected to the first unit and equipped with ports near its lower end which, when not closed by the first unit, permit circulation to discharge from inside of said lowering means into the space between said lowering means and the wall of the well hole and pass thence to the surface of the ground and constructed at its lower end to drive the packer into its seat by dropping said lowering means upon said packer; a third unit comprising a removable locking means consisting of slips which prevent relative movement between the first and second units during the lowering operations, said locking means to be removed from the well when the packer is seated; a fourth unit comprising a tubular sampling means adapted to be lowered through the lowering means and equipped at its lower end to rest on and make a tight seal with a complementary part of the first unit, thereby forming a continuous liquid tight tube from the surface of the ground to the bottom of the packer through which fluid originating below the packer can be drawn by bailing or pumping, said sampling means being of sufficient weight to hold the packer firmly against the seat in the well hole into which it has been driven, thereby sealing the well on the outside of the packer; a fifth unit comprising a device fixed to the upper end of the lowering means and equipped with a port for the admission of a circulation fluid between the second and fourth units and slidably connected by a stuffing box about the sampling means in such manner that the second unit or lowering means can be repeatedly raised and lowered about the stationary fourth unit or sampling means during sampling without interrupting the circulation, thereby preventing the lowering means from sticking to the wall of the well and also facilitating recovery of the apparatus upon the completion of the sampling.

5. A drilled well packer and sampler including a packer body adapted to be lowered to and against a previously drilled seat in the well hole, means for lowering the packer body to its seat, a sliding connection between said means and the packer body and whereby reciprocation may be imparted to said means after the packer has been seated and a packing cartridge between the packer body and the lowering means.

6. A drilled well packer and sampler including a tubular packer body adapted to be lowered to and against a previously drilled seat in the well hole, means for lowering the packer body to its seat, a sampler device

adapted to be lowered into a joint-forming engagement with a complementary part of said packer body after the latter has been seated, said packer body having a tubular spindle slidably fitted in the lower end of the lowering means and with the upper end of which spindle said sampler device forms a joint when it is placed in position and a cartridge of packing material on the spindle.

7. A drilled well packer and sampler including a tubular packer body adapted to be lowered to and against a previously drilled seat in the well hole, means for lowering the packer body to its seat, a packing cartridge above the packer body and a sampler device adapted to displace the cartridge and to be lowered into a joint-forming engagement with a complementary part of said packer body after the latter has been seated, said means including a head structure provided for circulation flow into the well and in which the sampler device is operatively mounted and packed, whereby the lowering means may be moved while the sampler device is resting on the seated packer body.

8. A drilled well packer and sampler including a tubular packer body adapted to be lowered to and against a previously drilled seat in the well hole, means for lowering the packer body to its seat, a packing cartridge above the packer body and a sampler device adapted to displace the cartridge and to be lowered into a joint-forming engagement with a complementary part of said packer body after the latter has been seated, said means including a head structure provided for circulation flow into the well and in which the sampler device is operatively mounted and packed, whereby the lowering means may be reciprocated while the sampler device is resting on the seated packer body.

9. A drilled well packer and sampler including a tubular packer body adapted to be lowered to and against a previously drilled seat in the well hole, means for lowering the packer body to its seat, a packing cartridge above the packer body and a sampler device adapted to displace the cartridge and to be lowered into a joint-forming engagement with a complementary part of said packer body after the latter has been seated, said means including a head structure provided for circulation flow into the well and in which the sampler device is operatively mounted and packed, whereby the lowering means may be reciprocated while the sampler device is resting on the seated packer body.

10. A drilled well packer and sampler including a packer body adapted to be lowered to and against a previously drilled seat in the well hole, tubular means for lowering the packer body to its seat and being provided adjacent its lower end with discharge ports, said packer body having a tubular spindle extending up into the lower end of said means and being provided with a portion adapted, in one position, to close the said discharge ports, whereby circulation fluid is forced through the tubular spindle and packer body, and a sampler device insertible into the lowering means and having a part complementary to the upper end of the said spindle whereby to make a joint therewith and through which device, spindle and packer body, samples may be taken from below the seated packer body.

11. A drilled well packer and sampler including a packer body adapted to be lowered to and against a previously drilled seat in the well hole, tubular means for lowering the packer body to its seat and being provided adjacent its lower end with discharge ports,

- said packer body having a tubular spindle extending up into the lower end of said means and being provided with a portion adapted, in one position, to close the said discharge ports, whereby circulation fluid is forced through the tubular spindle and packer body, and a sampler device insertible into the lowering means and having a part complementary to the upper end of the said spindle whereby to make a joint therewith and through which device, spindle and packer body, samples may be taken from below the seated packer body while circulation is maintained through the discharge ports.
15. 12. A drilled well packer and sampler including a packer body adapted to be lowered to and against a previously drilled seat in the well hole, tubular means for lowering the packer body to its seat and driving the packer body into its seat and providing at its lower end for discharge of fluid above the seated packer, a sealing medium adapted to be expanded in the well hole at the head of the seated packer to prevent downward flow of fluid, said packer being hollow and having a tubular spindle extending up into the lowering means to provide for taking samples of well product from below the seated packer, and a sampler adapted to be lowered into the tubular means and through which samples may be taken and providing for circulation downwardly in the tubular means.
13. A drilled well packer and sampler comprising a tapered packer body, tubular lowering means for lowering said packer body upon a previously formed seat in the well hole, means permitting a limited relative movement between said lowering means and said packer body, whereby said lowering means may be reciprocated in the well hole while said packer body remains seated, and a tubular sampling means adapted to be lowered within said lowering means and to seat upon said packer body so as to weight it against its seat and permit obtaining a sample of well fluid from below said packer body.
14. A drilled well packer and sampler comprising a tapered packer body and tubular lowering means slidably connected to the packer body whereby the lowering means may be reciprocated while the packer body is seated on a seat in the well, said lowering means having an external diameter substantially equal to the greatest external diameter of the packer so as to provide for the recovery of the packer.
15. A drilled well packer and sampler comprising a packer body, tubular lowering means for lowering the packer body, and an open ended tube upon the packer body extending upwardly into the lowering means so as to have a slidale connection therewith, whereby the lowering means may be moved while the packer remains seated, and a sample of fluid may be obtained from the well below the seated packer.
16. A drilled well packer and sampler comprising a tapered packer body adapted to seat upon a previously formed seat in a well hole, tubular lowering means for lowering the packer body onto the seat, and an open ended tube upon the packer body extending up into the interior of the lowering means providing for a limited sliding movement between the lowering means and the packer body, whereby the lowering means may be reciprocated while the packer remains seated in the well hole.
17. A drilled well packer and sampler comprising a packer body, tubular lowering means slidably connected to said packer body, and tubular sampling means adapted to be lowered within said lowering means and to seat upon said packer body, whereby the packer body may be held upon its seat in the well by the weight of the sampling means while the tubular lowering means is being reciprocated.
18. A packing apparatus for deep wells, comprising an outer pipe, an inner pipe, a packer slidably connected to the outer pipe, said packer and inner pipe being adapted to exclude fluid in the well above the seated packer from said inner pipe, while said outer pipe is being reciprocated and a sample of well fluid is being obtained from below the packer through said inner pipe.
19. A packing apparatus for deep wells comprising an outer pipe, an inner pipe, a packer slidably connected to said outer pipe, there being a longitudinal aperture through said packer communicating with said inner pipe, said packer and inner pipe being adapted to exclude fluid in the well above the seated packer from said inner pipe, while said outer pipe is being reciprocated and a sample of well fluid is being obtained from below the packer through the inner pipe.
20. A drilled well packer and sampler comprising a packer body, tubular lowering means slidably connected to said packer body, and tubular sampling means adapted to seat upon said packer body, there being discharge ports at the lower end of said lowering means adapted to permit circulation fluid to flow upon the inside and outside of said lowering means.
21. A drilled well packer and sampler comprising a packer body, tubular lowering means slidably connected to said packer body, and tubular sampling means supported upon the packer body, there being discharge ports at the lower end of said lowering means adapted to permit circulation fluid to flow upon the inside and outside of said lowering means while fluid is being drawn from below the packer through said sampling means.
22. A drilled well packer and sampler comprising a packer body, tubular lowering means

means slidably connected to said packer body, tubular sampling means adapted to seat upon said packer body, and means providing discharge ports at the lower end of said lowering means adapted to permit circulation fluid to flow upon the inside and outside of said lowering means while the packer is seated and the lowering means is reciprocated.

23. A drilled well packer and sampler comprising a packer body, tubular lowering means slidably connected to said packer body, tubular sampling means connected to the packer body, and means providing discharge ports at the lower end of said lowering means to permit circulation fluid to flow upon the inside and outside of said lowering means while the lowering means is reciprocated and fluid is drawn from below said packer body through the sampling means.

24. An apparatus for obtaining fluid from drilled wells comprising a packer having a passage through which well fluid is adapted to be withdrawn, said packer being adapted to be seated in a well, and a lowering pipe slidably connected to the packer whereby the lowering pipe may be reciprocated while fluid is being withdrawn from below the seated packer, said lowering pipe being of such a diameter as to prevent the well wall from caving in to a diameter materially smaller than the largest external diameter of the body of the packer.

25. An apparatus for obtaining fluid from drilled wells comprising a packer having a passage therethrough and a lowering pipe slidably connected to the packer whereby it may be reciprocated while the packer remains seated in a well and fluid is withdrawn from below the seated packer, said lowering pipe having an external diameter substantially equal to the greatest external diameter of the packer, whereby it will prevent the well wall from caving in to a size smaller than the packer may be recovered through.

26. A well sampling apparatus comprising a packer having a passage therethrough and adapted to be seated in a well, an outer lowering pipe connected to the packer adapted to lower it from the surface into the well, and an inner pipe adapted to be lowered within the outer pipe and form a connection with the passage through said packer, said lowering pipe being movably connected to the packer so that it may be continuously moved to prevent sticking while the packer remains seated without unseating or loosening the packer.

27. An apparatus for obtaining fluid from drilled wells comprising a downwardly tapered packer having a passage therethrough, and a pipe movably connected to the packer adapted to be continuously moved while the packer remains seated, said pipe having an external diameter substantially equal to the greatest external diameter of the packer so

as to provide for the recovery of the apparatus.

28. A well testing apparatus comprising a packer having a passage extending longitudinally therethrough, an imperforate inner pipe communicating with said packer and extending from said packer, when seated, to the surface, and an outer pipe disposed about said inner pipe and having a slideable connection with said packer so that it may be freely reciprocated while the packer remains seated without loosening the packer. 70

29. A well testing apparatus comprising a packer, a lowering string of pipe connected to the packer by means of a slideable connection, an imperforate hollow stem extending upwardly from the packer within said lowering string of pipe, there being a passage through the packer communicating with said stem, said slideable connection permitting the lowering string of pipe to be freely reciprocated without loosening the packer when seated, while well fluid is being drawn up through the seated packer and stem. 75

30. A well testing apparatus comprising a packer, means forming an imperforate conduit extending from below the packer, when seated, to the surface, said conduit and packer serving to prevent fluid in the well above the packer from entering said conduit, and an outer pipe surrounding said conduit above the packer, said outer pipe being slideably connected to the packer so as to be capable of being freely reciprocated without disturbing the packer or decreasing its sealing effectiveness. 90

31. A well packer and fluid sampler comprising an outer pipe, a packer movably connected to the outer pipe, and an inner pipe adapted to be lowered within the outer pipe to the packer, said inner pipe and packer being adapted to exclude fluid in the well above the packer from the interior of the inner pipe while the outer pipe is being moved to prevent sticking and a sample is being obtained from below the packer through the inner pipe. 95

32. A well packer and fluid sampler comprising an outer pipe, a packer movably connected to the outer pipe, and an inner pipe adapted to be lowered within the outer pipe to the packer, said outer pipe having ports provided therein near its bottom, said inner pipe and packer being adapted to exclude fluid in the well above the packer from the interior of the inner pipe while the outer pipe is being moved and circulation is taking place through the ports to prevent sticking while a sample is being obtained through the inner pipe from below the packer. 105

33. A well packer and fluid sampler comprising an outer pipe, a packer capable after having once been seated in a well of retaining its sealing effectiveness independently of forces exerted upon it by the outer pipe. 110

- means cooperating with the packer forming an imperforate conduit extending from the bottom of the packer upwardly within the outer pipe, and means providing a slidable connection between the outer pipe and said packer whereby the outer pipe may be reciprocated without disturbing the seated packer while a sample is being obtained through the conduit from below the packer.
- 10 34. A well packer and fluid sampler comprising an outer pipe, a packer capable after having once been seated in a well of retaining its sealing effectiveness independently of forces exerted upon it by the outer pipe, an inner pipe disposed within the outer pipe and connected to the packer and serving to cause the packer to maintain its sealing effectiveness, and means providing a slidable connection between the outer pipe and said packer whereby the outer pipe may be reciprocated while a sample is being obtained through the inner pipe from below the packer.
- 15 35. A well packer and fluid sampler comprising an outer pipe, a packer capable after having once been seated in a well of retaining its sealing effectiveness independently of forces exerted upon it by the outer pipe, means providing a limited slidable connection between the outer pipe and packer whereby the outer pipe may be reciprocated while the packer remains seated, and an inner pipe adapted to be lowered within the outer pipe and caused to be connected with said packer whereby a sample from below the packer may be obtained from below the packer through the inner pipe while the outer pipe is being reciprocated to prevent sticking.
- 20 36. A well packer and fluid sampler comprising an outer pipe, a packer capable after having once been seated in a well of retaining its sealing effectiveness independently of forces exerted upon it by the outer pipe, means providing a slidable connection between the outer pipe and packer whereby the outer pipe may be reciprocated while the packer remains seated, and an inner pipe adapted to be lowered within the outer pipe and caused to be connected with said packer, said inner pipe serving to cause the packer to maintain its sealing effectiveness while the outer pipe is being reciprocated and a sample is being obtained through the inner pipe from below the seated packer.
- 25 37. A well packer and fluid sampler comprising an outer pipe, a packer having a downwardly exposed seating surface movably connected to the outer pipe, and an inner pipe adapted to be lowered within the outer pipe so as to establish communication with a passage through said packer, said outer pipe having ports provided therein as and for the purpose described.
- 30 38. A recoverable well packer and fluid sampler comprising a tubular packer pro-
- vided with a downwardly tapered external sealing surface, tubular lowering means connected to said packer and provided with a discharge port adjacent the lower end thereof, said packer having a tubular extension 70 extending up into the lower end of said lowering means and provided with a seat at the upper end thereof, and a sampler tube within said lowering means seated by gravity upon said seat, said tube, extension and packer forming a passage communicating with the space below said packer and extending upward therefrom, the wall of said passage being liquid tight against entry of liquid into said sampler tube above said sealing surface. 75
39. A drilled well packer and sampler comprising a packer body provided with an external downwardly tapered sealing surface, tubular lowering means connected to said packer body, tubular sampling means adapted to be lowered through the lowering means to seat upon said packer body, and means providing discharge ports at the lower end of said lowering means.
- In testimony whereof I have signed my name to this specification.
